United States Patent Office.

SHILOH W. DURHAM, OF IPAVA, ILLINOIS.

Letters Patent No. 74,807, dated February 25, 1868.

IMPROVEMENT IN STRAP-FASTENER.

The Schedule referred to in these Letters Patent and making part of the same.

TO ALL WHOM IT MAY CONCERN:

Be it known that I, SHILOH W. DURHAM, of Ipava, in the county of Fulton, and State of Illinois, have invented a new and improved Buckle or Fastener for Straps, &c.; and I do hereby declare that the following is a full, clear, and exact description thereof, which will enable others skilled in the art to make and use the same, reference being had to the accompanying drawings, forming a part of this specification.

The present invention relates to an improved fastener or buckle for securing and fastening the end of a strap when turned over at its end upon itself for forming a loop, the construction of which, according to this invention, will be now described, reference being had to the accompanying plate of drawings, in which—

Figure 1 is a side or face view of a strap with it applied, and

Figure 2 a section taken in the plane of the line x x , fig. 1.

Similar letters of reference indicate corresponding parts.

A, in the drawings, represents my improved fastener, which is formed of a plate, B, having a loop, C, at one end, and a loop, D, near the other, carrying a tongue, E, upon its under side edge F. G, a strap, turned over upon itself at one end, and by such end inserted in the loops C and D of the plate, with the loop H of such strap projecting from the end I of the plate, and the strap so secured in place by the insertion of the tongue E in one of its holes. J, a ring, shown as being carried in the loop of the strap, and which is placed therein before inserting the strap in the loops of the fastener.

Having thus described my invention, what I claim as new, and desire to secure by Letters Patent, is—

The strap-fastener, constructed as described, consisting of the plate B, having, upon one of its sides, the loops C D, the latter bearing the tongue E, whose inner end fits within the strap between the loops C D, as herein shown and described.
